Specification of Letters Patent. Patented Apr. 26, 1921.

Application filed April 9, 1920. Serial No. 372,474.

To all whom it may concern:

Be it known that we, WILLIAM K. BOOTH and WILLIAM L. MORRIS, citizens of the United States, residing at Chicago, in the county of Cook and State of Illinois, have invented a new and useful Improvement in Electric Furnaces, of which the following is a specification.

This invention relates particularly to electric furnaces of the oscillating or rotary type; and the primary object is to provide a furnace of this type with means for effectively cooling the electrode bearings, with which the furnace is equipped.

The invention is illustrated, in its preferred embodiment, in the accompanying drawings, in which—

Figure 1 represents an end elevational view of a rotary furnace equipped with the improvements; Fig. 1^a, a sectional view parallel with the end of the furnace and showing a mounting-plate which appears in Fig. 1; Fig. 1^b a sectional view of a water-cooled electrode bearing which appears also in Fig. 1^a; Fig. 1^c, a broken sectional view showing one of the universal joints of the water-pipe employed; Fig. 2, an end elevational view of the opposite end of the machine; Fig. 2^a, a sectional view parallel with the end of the furnace and showing the mounting-plate which appears also in Fig. 2; Fig. 3, a broken longitudinal sectional view of the end portion of the furnace shown in Fig. 1; Fig. 3^a, a broken sectional view taken as indicated at line 3^a of Fig. 1, and showing a detail of the annular track which serves also as an annular contact member; Fig. 3^b, a broken longitudinal vertical section of the furnace, taken as indicated at line 3^b of Fig. 1; Fig. 4, a broken vertical section taken as indicated at line 4 of Fig. 2 and showing the end-portion of the furnace which is viewed in Fig. 2; and Fig. 4^a, an enlarged vertical sectional view showing a detail of a water-discharge pipe.

In the construction illustrated, A represents a base, or frame, in which are journaled longitudinal shafts A' equipped with rollers A², upon which the furnace-body is supported; B, an electric motor geared to the shaft A'; C, a furnace-body of cylindrical form which is equipped with annular insulating tracks C', which serve also as annular contact members; D, a mounting-

plate carried by one end of the furnace and equipped with an electrode frame D', on which is mounted an adjustable electrode clamp D² carrying an electrode D³; E, a mounting-plate carried by the opposite end of the furnace and equipped with an electrode frame E', on which is mounted an adjustable electrode-clamp E², which carries an electrode E³, the mounting-plate E being secured to a charging door E⁴ mounted on the end of the furnace; F, F', brushes, or contact members, mounted on the base A and engaging the annular contact members C' of the furnace-body; G, G', water-cooled electrode bearings or cooling-collars for the electrodes D³ and E³ respectively; and G² a water-circulating system which serves to circulate water through the electrode-bearing G and then through the electrode-bearing G'.

The base, or frame, A, may be of any suitable construction; and the rollers which support the furnace-body may be actuated by any suitable mechanism to turn the furnace-body about its axis. The movement of the furnace-body may be an oscillating movement, or a continuous rotary movement, preferably the latter, as illustrated.

The furnace-body C may be constructed in any desired manner. It is shown as comprising a steel shell 1 and a refractory lining 2. An axial charging opening 3 is provided at one end of the furnace, this opening being closed by the door E⁴. The other end of the furnace is shown provided with a discharge-spout 4.

The mounting-plate D is shown secured, by means of bolts 5, to angle-members 6, which are secured, in turn, to angle-members 7 riveted to one end of the steel shell 1. The electrode-supporting frame D' comprises, in addition to the mounting-plate D, horizontal guide-rods whose inner ends are firmly secured to the plate D. The electrode clamp D² is slidably mounted on the rods 8 and is actuated by screws 9, which are equipped with pinions 9^a engaged by a gear 10 of a tubular member 10^a, which is journaled in the end plate 8^a which constitutes a part of the frame D', the outer end of the member 10^a being provided with a hand-wheel 10^b. Rotation of the member 10^a through the medium of the hand-wheel causes the gear 10 to actuate the screws 9,

and move the electrode-clamp inwardly, or outwardly, as desired.

The mounting-plate E, which forms the base of the electrode-supporting frame E', is secured to the charging door E⁴ by means of bolts 11. The door is mounted to swing on a vertical pivot 12 carried by a suitable frame 13 secured to the end wall of the furnace. The electrode-supporting frame E' comprises, in addition to the plate E, guide-rods 14 and an outer end plate 14^a. The electrode-clamp E² is mounted on the guides 14 and actuated by screws 15 equipped with pinions 15^a, which, in turn, are actuated by a gear 16 formed integrally with a tubular member 16^a journaled in the plate 14 and equipped with an annular hand-wheel 16^b.

The water-cooled collar G for the electrode D³ comprises a hollow annular metal member, which is set in a counter-sink 17 at the outer end of a central perforation 17^a in the end-lining of the furnace.

The water-cooled member G' for the electrode E³ comprises a hollow collar which is set in a counter-sink 18 at the outer end of a central perforation 18^a in a block of refractory material 19, which constitutes the lining of the door E⁴. The brushes, or stationary contact members, F, F', may be of any suitable construction. The brushes are charged by an electric circuit (not shown), and the annular contact members C' are thus energized. Said annular contact members are connected, by flexible conductors 20, with the electrode-clamps. The circuit is completed through the clamps of the electrodes, and the furnace operates through an arc between the inner ends of the electrodes.

The water-circulating system G², which circulates water through the electrode-bearing G and thence through the electrode-bearing G', comprises a stationary inlet pipe 21, through which water under pressure from any suitable source may enter; a pipe 22 having a vertical swivel portion 22^a, disposed at one side of the furnace near one end thereof, and which is connected by a vertical swivel joint 22^b with the inlet pipe 21, the pipe 22 having a portion 22^c which extends substantially parallel with the ends of the furnace, and having also an outwardly-extending portion 22^d which extends parallel with the electrode frame and projects some distance beyond the outer end thereof; a transverse pipe-joint 23 which has universal connection 23^a with the outer end of the portion 22^d of the pipe 22, and which has universal connection 23^b at its opposite end; a pipe 24 extending substantially parallel with the electrode frame and having its outer end connected with the pipe-joint 23 through the universal joint 23^b and having its inner end screwed into an internally-threaded boss 24^a with which the mounting plate D is provided; a rubber hose 25

through which the water passes from the pipe 24; a pipe 26 connected with the hose 25 and leading into the chamber 27 of the electrode-bearing G; a return pipe 28 leading outwardly from the electrode-bearing G; a rubber hose connection 29 through which the water passes from the pipe 28; a longitudinal pipe 30 (Figs. 1 and 3^b); which extends longitudinally along the outer surface of the furnace-body; a rubber hose 31 through which the water passes from the pipe 30 to the mounting-plate E; a pipe 32 which communicates with the hose 31 and extends inwardly to the electrode-bearing G', where it communicates with the water chamber 33 of said bearing; a return pipe 34 leading outwardly from said bearing; a rubber hose 35 which receives the water from the pipe 34; a pipe 36 which receives the water from the hose 35, said pipe 36 having its inner end securely mounted in a boss 36^a of the plate E and having its outer end extending some distance beyond the outer end of the electrode frame E'; a transverse pipe joint 37 having one end connected, by a universal joint 37^a, with the pipe 36, and having the other end equipped with a universal joint 37^b; an inclined pipe 38 having its outer end connected with the swivel joint 37^b and having its inner, lower end communicating with a passage 38^a in a swivel member 38^b; a vertical pipe 39 which receives the water from the passage 38^a, and a stationary discharge pipe 40, which communicates through a vertical swivel joint 40^a with the pipe 39.

A detail of the universal joints employed as pipe joints is shown in Fig. 1^c, by way of example. It is unnecessary to describe the joint in detail, as it will be readily understood, and any suitable joint can be employed.

The vertical portion 22^a of the admission pipe 22 extends through a tubular standard 41. Above said standard, the pipe 22 has secured thereto a collar 42 which bears on the upper end of the standard. It will be understood, however, that the swivel joint 22^b, which is located below the standard, affords swivel connection between the stationary intake pipe 21 and the vertical portion 22^a of the pipe 22.

As has been explained, the pipe 24 extends mainly parallel with the electrode, and is fixedly carried by the mounting-plate D. Thus, as the furnace rotates, the outer end of the pipe 24 and the universal joint 23^b carried thereby describe a circle; and the cross-pipe joint 23 oscillates about the axis of the outer end of the pipe 24, which has a movement like a crank. The cross-pipe 23 being connected with the pipe 22 by a universal joint, and the pipe 22 being vertically swiveled, it will be understood that the pipe 22 can turn in its ver-

120 125 130

tical bearing as may be necessary during the rotation of the furnace.

As has been stated, the inner end of the pipe 24 is screwed into a hollow boss 24^a of the mounting-plate D. The mounting-plate is provided with cored passages for the ends of the flexible tube 25, as will be clearly understood from Fig. 1^a. The flexible tube 29 also extends through a cored 10 passage 43 in the plate D. The pipes 26 and 28 which conduct the water to and from the electrode-bearing G are provided with suitable elbows and nipples for connection with the hose 25 and 29.

15 At the opposite end of the furnace, the pipe 36 is rigidly mounted on the plate E, and its outer end describes a circle, as the furnace rotates. The cross-pipe 37 oscillates about the outer end of the pipe 36 as 20 a center during rotation of the furnace, the outer end of the pipe 36 having thus a crank-like connection. The link, or pipe, 38, oscillates about its vertical axis at 39, as may be necessary. The construction at 25 the discharge end of the water circulating system is such, also, that the furnace door can be swung open to enable the furnace to be charged, without disturbing the water circulation. Fig. 2^a shows how the mounting-plate D is suitably cored to accommodate the ends of the bent hose 35 and the 30 end of the hose 31. The construction is virtually the same as at the other end of the furnace.

35 The construction described provides a water-circulating system for cooling the electrodes, or the electrode-bearings, of a furnace of the rotary type. The construction permits the charging door of the furnace to be opened and closed without disarranging the system. It may be stated, also, that the use of water-cooled collars on 40 bearings for the electrodes, said collars being composed of metal, serves to provide 45 for the electrodes suitable bearings, in which the electrodes will not stick. This is of particular importance in melting brass or other metal containing a volatile constituent, such as zinc, as the tendency of 50 the bearing to freeze to the electrode is obviated. Such difficulty has been found to exist where ordinary graphite bearings have been employed for the electrodes.

55 Referring to Fig. 2, it will be noted that the door E^a can be opened by swinging it outwardly and to the right about the pintle 12. If we assume the furnace to be rotated 180°, the door may be opened by swinging it outwardly and to the left. It will be noted that the pipe-connections permit the door to be opened in either of these positions, and the feature of swiveling the pipe 38 at or near the vertical median plane of the furnace facilitates this result.

60 65 It may be added that the electrode-collars

G and G', while in the nature of bearings, are not depended upon to support the electrodes but chiefly serve as cooling-collars for the electrodes and as rather loose stuffing-boxes in the ends of the furnace. 70

The foregoing detailed description has been given for clearness of understanding only, and no unnecessary limitation should be understood therefrom, but the appended claims should be construed as broadly as 75 permissible, in view of the prior art.

What I regard as new, and desire to secure by Letters Patent, is:

1. In an electric furnace, the combination of a furnace-body provided with a refractory lining, means for supporting said body and rotating it to any desired extent about its axis, electrodes extending through the end walls of said body at its axis of rotation, adjustable electrode supports mounted 80 on the ends of said body and carrying said electrodes, means for supplying current to said electrodes, metal collars for said electrodes in the end walls of said body provided with water passages, and means for 85 circulating water through said collars during rotative movement of the furnace-body about said axis.

2. In an electric furnace, the combination of a furnace-body provided with a refractory lining, means for supporting said body and turning it about its axis, electrodes extending through the end walls of said body at the axis of rotation, adjustable electrode 95 supports mounted on the ends of said body 100 and carrying said electrodes, means for supplying current to said electrodes, metal collars in the end walls of said body provided with water passages, mounting-plates disposed outside the end walls of said furnace-body and independent of said collars, and means for circulating water through said 105 collars when the furnace-body is moving, including in-going and return pipes communicating with the water passages of said 110 collars which are connected with said mounting plates.

3. In an electric furnace, the combination of a furnace-body provided with a refractory lining, means for supporting said body and turning it about its axis, electrodes extending through the end walls of said body at said axis, adjustable electrode supports mounted on the ends of said body and carrying 115 said electrodes, means for supplying current to said electrodes, metal collars in the end walls of said body provided with water passages, and means for circulating water through said collars when the furnace-body is moving, including pipes carried by said 120 mounting-plates and projecting outwardly therefrom substantially parallel with the electrodes, pipes connected with said mounting-plates and communicating with the water passages in said collars, one of said 125 130

last-mentioned pipes communicating with the corresponding first-mentioned pipe, and pipes having jointed connection with said first-mentioned pipes at points beyond the 5 electrodes and electrode - supporting means, said jointed connections permitting rotation of the furnace about said axis.

4. In an electric furnace, the combination of a rotating furnace-body provided with 10 a refractory lining, electrode - supporting frames projecting from the ends thereof, electrode-clamps adjustably mounted on said frames, electrodes carried by said clamps and extending through the end walls of the 15 furnace-body, means for supplying electric current to the electrodes, metal collars for the electrodes mounted in the end walls of the furnace and provided with water passages, and means for circulating water 20 through said collars comprising pipes supported on the end walls of the furnace-body and extending parallel with and projecting beyond the outer ends of the electrode-supporting frames, said pipes communicating 25 with the passages of said collars, cross-pipes having swivel connections at one end with the outer ends of said first-named pipes, and pipes having swivel connection with the other ends of said cross pipes.
- 30 5. In an electric furnace, the combination of a furnace-body provided with a refractory lining, means for supporting said body and rotating it about its axis, an electrode-supporting frame extending from the end 35 wall of said body, an electrode-clamp adjustably mounted on said frame, an electrode carried by said clamp and extending through the end wall of said body, means for supplying current to said electrode, a 40 metal collar in the end wall of said body provided with a water passage, a mounting-plate constituting the inner end of an electrode frame, inlet and outlet pipes connected with said mounting-plate and communicat- 45 ing with the passage of said collar, a water pipe having its inner end secured to said mounting-plate and having its outer end projecting beyond the outer end of said frame, said pipe communicating with one 50 of the pipes leading to said collar, a cross- pipe having universal connection with the outer end of said second-mentioned pipe, a pipe having universal connection with the other end of said cross-pipe, and a pipe hav- 55 ing swivel connection with said last-mentioned pipe.

6. In an electric furnace, the combination of a rotating furnace-body provided with a refractory lining, electrode - supporting 60 frames projecting from the end walls of said body, electrode-clamps adjustably mounted on said frames, electrodes carried by said clamps and extending through the end walls of said body, jacketed collars for said 65 electrodes in the end walls of said body,

75 pipes extending substantially parallel with the electrode-supporting frames and projecting beyond the outer ends of said frames, said pipes being in communication with said jacketed collars, a water conduit connecting 70 said jacketed collars, and inlet and discharge water pipes having universal connection with the outer ends of said pipes which project beyond the ends of the electrode frames.

7. In an electric furnace, the combination of a rotating furnace-body provided with a refractory lining, electrode - supporting frames projecting from the end walls of 80 said body, electrode-clamps adjustably mounted on said frames, electrodes carried by said clamps and extending through the end walls of said body, jacketed collars for said electrodes in the end walls of said body, pipes extending substantially parallel with 85 the electrode-supporting frames and projecting beyond the outer ends of said frames, said pipes being in communication with said jacketed collars, a water conduit connecting said jacketed collars, cross-pipes 90 having universal connection with the outer ends of said projecting pipes, pipes having universal connection with said cross-pipes, and inlet and discharge pipes having swivel connection with said last-mentioned pipes. 95

8. In an electric furnace, the combination of a rotating furnace-body provided with a refractory lining, a mounting-plate secured on one end of said body, an electrode-supporting frame carried by said mounting-plate, an electrode-clamp adjustably mounted on said frame, an electrode carried by said clamp and extending through the end wall of said body, a chambered bearing for 100 said electrode mounted in the end wall of said body, inlet and outlet pipes connected with said mounting-plate and communicating with said bearing, a pipe having its inner end secured to said mounting-plate and communicating with the inlet pipe of 105 said bearing and having its outer end projecting beyond the outer end of said frame, a cross-pipe having universal connection with the projecting pipe, another pipe having universal connection with said cross- 110 pipe and having a vertical swivel portion, and an inlet pipe having swivel connection with the vertical portion of said last-mentioned pipe. 115

9. In an electric furnace, the combination 120 of a furnace body and means for actuating it about its axis, said body being provided with a refractory lining, a mounting-plate carried by an end wall of the furnace body and provided with pipe passages, an electrode-frame carried by said mounting-plate, an electrode-clamp adjustably mounted on 125 said frame, an electrode carried by said clamp and extending through the end wall of said body at said axis, a collar for said 130

electrode provided with a water passage, pipes communicating with said water passage and having portions extending through the pipe passages of said mounting-plate, 5 and means for admitting water to and educting water from said pipes while the furnace-body is in motion.

10. In an electric furnace, the combination of a rotating furnace-body provided with a refractory lining, an adjustable electrode extending through an end wall thereof, a mounting-plate carried by said end wall, an electrode-bearing in the end wall at the axis of rotation provided with a water 15 passage, a pipe projecting from said mounting-plate substantially parallel with the electrode, an inlet pipe leading to said bearing, a hose carried by said mounting-plate and connecting said pipes, an outlet pipe 20 leading from said bearing, a conduit supported by said mounting-plate and communicating with said outlet pipe, and means for supplying water to the pipe projecting from said mounting-plate during rotation of 25 the furnace-body.

11. In an electric furnace, the combination of a rotating furnace-body provided with a refractory lining, electrode bearings mounted in the end walls of said furnace- 30 body and provided with water passages, a water conduit connecting the passages of said bearings, said pipe having a portion extending along the outer wall of the furnace-body from one end of the furnace to the 35 other, means for supplying water under pressure to the passage in one of said bearings, and means for discharging water from the passage of the other of said bearings.

12. In an electric furnace, the combination of a furnace-body, means for supporting said body and turning it about its axis, a charging door mounted on one end of said body, an electrode-frame carried by said charging door, an electrode-clamp adjustably 45 mounted on said frame, an electrode carried by said clamp and extending through said door, an electrode-collar in said door provided with a water passage, and means adapted to circulate water through said collar during the actuation of the furnace body, said means being adapted to permit said door to be opened without disconnecting the water circulating means.

13. In an electric furnace, the combination of a rotating furnace-body, an axial charging door mounted on one end of said body, an electrode frame carried by said door, an electrode-clamp adjustably mounted on said frame, an electrode carried by 55 said clamp and extending through said door, a jacketed electrode-bearing in said door, means for admitting water to said bearing, a pipe extending outwardly from said door and communicating with said bearing, the 60 outer end of said pipe projecting beyond

the electrode frame, a stationary pipe disposed near the base of the furnace, pipe connections between said stationary pipe and the pipe projecting beyond the electrode-frame, said pipe connection permitting rotation of the furnace-body and enabling the charging door to be opened without interfering with the water circulating system.

14. In an electric furnace, the combination with a rotary furnace body, electrode-frames projecting from the ends thereof, electrodes adjustably carried by said frames and extending through the ends of the furnace-body, and means for supplying electric current to said electrodes, of jacketed bearings for said electrodes, means for circulating water through said bearings, including eccentrically disposed pipes which project beyond the outer ends of the electrode-frames, and jointed inlet and discharge pipes connected with the outer ends of said projecting pipes, and stationary inlet and discharge pipes having jointed connections with said last-mentioned pipes, whereby circulation through said bearings will be maintained during rotation of said furnace-body.

15. In an electric furnace, the combination of a furnace-body equipped at one end with a swinging door, an electrode frame mounted on said door, an electrode carried by said frame and extending through the door, an electrode bearing in said door provided with a water chamber, and water circulating means comprising a pipe communicating with said water chamber, said pipe permitting the door to be opened and closed, a pipe carried by said door and projecting beyond the outer end of said electrode-frame, the inner end of said pipe communicating with said water chamber, a cross-pipe having universal connection with the outer end of said projecting pipe, an inclined pipe having universal connection at its outer end with said cross-pipe and having swivel connection at its inner end in the base of the furnace, and a stationary discharge-pipe having swivel connection with said last-mentioned pipe.

16. The combination of a rotary furnace-body equipped at its end with a swinging door, an electrode-frame mounted on said door, an electrode adjustably mounted on said frame, a cooling-collar for said electrode mounted on said door, and pipe-connections for said cooling-collar, including a pipe mounted on said door and projecting beyond the electrode-frame, and a pipe communicating with said first-named pipe and having a swivel connection disposed in approximately a longitudinal median plane of the furnace-body.

WILLIAM K. BOOTH.
WILLIAM L. MORRIS.
